FRANK L. SCHWARZ, JR., OF HIGHLAND PARK, MICHIGAN, ASSIGNOR TO SCHWARZ FOUNDRY CO., OF DETROIT, MICHIGAN, A CORPORATION OF MICHIGAN

SHADE ROLLER ADJUSTING DEVICE

Application filed March 16, 1931. Serial No. 522,810.

The present invention pertains to a novel window shade roller adjusting device of a type particularly adapted for use in combination with either casement or double hung windows.

In residences or public buildings having a number of symmetrically arranged windows it is desirable that the window shades should all hang so that the lower ends of all the shades are level. Ordinary window shade rollers are equipped with two pawls which hold the roller against backward rotation as result of pressure of the spring contained therein and these pawls are only capable of stopping the movement of the roller after it has travelled a half revolution and the result is that the lower ends of the shades can only be adjusted within a range corresponding to the amount of the shade which is unrolled by a half revolution of the roller. The only manner in which the shades can be accurately adjusted is by taking down the roll and cutting a portion of the shade away and this obviously takes considerable time and expense and therefore the present invention contemplates the provision of means for inexpensively and accurately adjusting the window shades so that any number of them may be arranged so that they unroll so that their lower ends will be level.

The present invention further contemplates the provision of an adjustable supporting device for the shade roller which makes it impossible for the shade roller to be removed accidentally.

With the above and other ends in view the invention consists in matters hereinafter set forth and more particularly pointed out in the appended claims, reference being had to the accompanying drawings, in which

Figure 1 is a fragmentary view of a window shade roller having one end supported in one of the present adjustable supports;

Fig. 2 is a side elevation of the outer face of the present device;

Fig. 3 is a side elevation of the inner face;

Fig. 4 is an illustration of the ratchet faced disk which holds the shade in any position of adjustment;

Fig. 5 is a side elevation of the supporting bracket.

Fig. 6 illustrates the adjustable device in combination with a bracket adapted for use in combination with a double hung window, 55

Fig. 7 is a top plan view thereof.

Like characters of reference are employed throughout to designate corresponding parts.

In Fig. 1 the numeral 1 indicates a conventional window shade mounted in the usual manner upon a roller 2. Within the roller is a mechanism which causes the roller to roll the shade thereon and according to conventional standards the roller is provided with means capable of stopping movement of the roller backwardly at intervals of every half revolution providing the projecting angular member 3 is held against rotation in a suitable bracket. The present invention aims to hold this projecting member 3 by means which ordinarily prevents rotation thereof but which will permit rotation thereof under certain conditions for the purpose of adjustment when such is desired. 75

A bracket 4 is provided with a pair of ears 5 arranged at right angles thereto to facilitate its attachment to a window. The bracket is dished as at 6 to form a dome shaped portion projecting toward the roller and in this dome shaped portion is formed a keyhole slot 7.

A plurality of ears 8 are formed on the bracket 4 and are bent over the edge of a disk 9 which is dished as at 10 to fit over the dome shaped portion of the bracket. In the dished portion of the disk is formed a slot 11 of a width so that it receives the angular member 3 on the roller in a manner so that the member 3 and disk cannot rotate relative to each other. 85

A slight angular projection 12 is formed on the face of the bracket 4 and a series of notches 13 are formed in the adjacent face of the disk 9 and the ears 8 hold the disk 95 so that the projection 12 extends into one of the notches to ordinarily resist rotation of the disk relative to the bracket.

In using the present device it will be understood that it applies to only one end of the 100

roller and in order to mount the roller there-
in the two slots 7 and 11 are aligned as illus-
trated in Fig. 6. After the member 3 is in-
serted in the aligned slots the disk 9 is ro-
tated a part of a revolution so that the slots
5 are no longer in alignment with each other,
this latter position being illustrated in Figs.
2 and 3. When the slots are out of align-
ment in this position the member 3 cannot be
removed from the slots.

10 If the lower ends of the shades can not be
adjusted to the correct height by means of the
conventional pawl and ratchet mechanism
the disk may be rotated to bring them to the
correct height for it is obvious that the slot
15 11 in the disk 9 holds the member 3 against
rotation and therefore when the disk is ro-
tated the member 3 is also rotated and a por-
tion of the shade is rolled onto or off of the
roller. The ears 8 hold the disk close enough
20 to the bracket so that the projection extends
into one of the notches 13 a sufficient distance
as to require considerable pressure upon the
disk in order to spring the disk and the
bracket apart in order that the projection 12
25 may snap from one notch to the next in order
that it may hold the disk 10 against rotation
at any stage of rotation that attains the de-
sired adjustment.

30 In Figs. 6 and 7 the bracket 4 is formed
with ears 14 extending outwardly parallel
thereto for use in combination with windows
having a supporting surface projecting at
right angles to the axis of the roller 2.

35 Although a specific embodiment of the
present invention has been illustrated and
described it is to be understood that various
changes may be made in the details of con-
struction without departing from the spirit
40 of the invention as defined in the following
claims, and such changes are contemplated.

What I claim is:

1. A device of the character described com-
prising a bracket having a dome shaped pro-
jecting portion with an opening formed
45 therein, an angular projection formed on said
bracket, a disk having a slotted dished por-
tion fitting said dome shaped projection, and
notches formed in said disk adapted to re-
ceive said angular projection.

50 2. A device of the character described com-
prising a bracket having a dome shaped pro-
jecting portion with an opening formed
therein, an angular projection formed on said
55 bracket, a disk having a slotted dished por-
tion fitting said dome shaped projection,
notches formed in said disk adapted to re-
ceive said angular projection, and ears
60 formed on said bracket and bent over said
disk to hold the latter so that said angular
projection extends into one of said notches.

65 3. A device of the character described com-
prising a bracket, a dome shaped projection
formed on said bracket and having an open-
ing therein, a disk having a dished portion

fitting over said dome shaped projection, a
slot formed in said disk, and ratchet means
for preventing rotation of said disk relative
to said bracket.

4. A device of the character described com-
prising a bracket, a dome shaped projection
formed on said bracket and having an open-
ing therein, a disk having a dished portion
70 fitting over said dome shaped projection, an
angular projection formed on said bracket,
notches formed in said disk, and ears formed
75 on said bracket and bent over said disk to
hold the latter so that said angular projection
extends into one of said notches.

5. A device of the character described com-
prising a bracket, a dome shaped projecting
portion formed on said bracket, a key hole
slot formed in said dome, a disk having a
dished portion received on said dome, a slot
80 formed in said dished portion, an angular
projection on said bracket, notches in the
85 face of said disk, and ears on said bracket
bent over said disk and holding the latter so
that said angular projection extends into one
of said notches.

90 In testimony whereof I affix my signature.
